CLAIM

The ornamental design for a mobile device camera adapter, as shown and described.

DESCRIPTION

FIG. 1 is a front perspective view of a mobile device camera adapter showing our new design;

FIG. 2 is a back perspective view thereof;

FIG. 3 is a front elevation view thereof;

FIG. 4 is a back elevation view thereof;

FIG. 5 is a side elevation view thereof;

FIG. 6 is an opposite side elevation view thereof;

FIG. 7 is a top plan view thereof; and,

FIG. 8 is a bottom plan view thereof.

The broken lines depict portions of the mobile device camera adapter in which the design is embodied that form no part of the claimed design.
